Primary Examiner — Susan Moon Lee(74) *Attorney, Agent, or Firm* — Mikowski & Leonard, LLC; Justin C Mikowski; Lauren A Brown(57) **CLAIM**

The ornamental design for an adjustable height animal feeder, as shown and described.

DESCRIPTION

FIG. 1 is a perspective view of an adjustable height animal feeder;

FIG. 2 is a right side view thereof;

FIG. 3 is a left side view thereof;

FIG. 4 is a front view thereof;

FIG. 5 is a rear view thereof;

FIG. 6 is a top view thereof; and,

FIG. 7 is a bottom view thereof.
